ELECTRICAL-FIXTURE CONSTRUCTION

Application filed June 12, 1924. Serial No. 719,670.

This invention relates to electrical fixtures, and has for its object a particularly simple and efficient construction by which the fixture is readily attachable to a support, and by 5 which an attaching member for an electrical appliance as a lamp or other appliance is assembled in the base to produce a simple compact arrangement.

The invention consists in the novel features 10 and in the combinations and constructions hereinafter set forth and claimed.

In describing this invention reference is had to the accompanying drawings in which like characters designate corresponding 15 parts in all the views.

Figure 1 is a sectional view of this fixture, the same being shown as attached to a support on a wall or ceiling.

Figure 2 is an inner face view of the base. 20 This invention comprises generally a base having means for attachment to a support on a wall or ceiling or other part by an interlocking movement as a partial rotary movement of the base, and also a simple relative 25 arrangement of an attaching member for an electrical appliance with respect to said means.

1 designates the base which is usually formed up of comparatively light sheet metal 30 in the form of a canopy, the base having a tubular neck 2. The means for attaching the base to a support comprising a part associated with the base and arranged on the interior of the base at the inner end of the 35 passage of the neck 2, and provided with means for interlocking with a support for the fixture by a partial rotary movement of the base. The part associated with the base is here shown as a bridge 3 extending across 40 the passage of the neck at the inner end thereof, and secured as at its ends to the base by suitable means as rivets 4. The bridge is here shown as formed with open ended slots 5, which are preferably arc-shaped and 45 arranged opposite each other and curved

about the same center which is usually the center of the base. These slots open through opposite side edges of the bridge, that is one slot opens through one side edge and the other through the opposite side edge. 50

The support for interlocking with the base or the bridge 3, as here shown includes headed members as rods or screws 6 threading into a collar 7 on a nipple 8 which is secured to a wall or ceiling, it usually threading into 55 a plate or box 9 secured to a wall or ceiling 10 in any suitable manner as by screws 11. The collar 7 usually threads on the nipple 8 and is secured thereto against unintentional turning by a set screw 12. The plate or box 60 9 is provided with inlet and outlet openings for electric wires or for conduits 13 enclosing said wires.

In applying the base 1 to a ceiling the 65 collar 7 is first attached to the nipple with the screws thereon, and then the base is secured to these screws, by a partial rotary movement which causes the screws 6 to move into the slots 5 with the heads thereof hooking under the bridge; and then tightening 70 the screws.

Preferably the entrance ends of the slots are widened for facilitating the entrance of the screws 6 therein.

14 designates the casing of any electrical 75 appliance, as a lamp socket. These casings being provided with various types of contacting or compression members for interlocking with an attaching member as a ring carried by a fixture usually by a partial rotary movement as will be understood by those skilled in the art.

15 designates the attaching member formed in any suitable manner to interlock with the 80 case 14.

The attaching member is arranged in the neck 2 and thrusts at its outer edge against an internal annular flange 16 at the outer end of the neck and has means for interlock- 90

ing with the bridge to prevent turning of the attaching member.

The means for interlocking the attaching ring 15 with the bridge 3 as here shown comprises shoulders 17 usually struck from the bridge 3, these shoulders projecting toward the ring, and lugs on the ring for interlocking with the shoulders. Preferably the ring is formed with diametrically opposite arms 18 extending from the ring toward the bridge, these arms terminating in laterally turned feet or lugs 19 which are notched or formed with bifurcations for embracing the shoulders 17.

15 As the base 1 is formed of comparatively light sheet metal, preferably a reinforcing ring 20 is located in the neck 2 between the attaching ring 15 and the neck, the reinforcing ring thrusting at its lower end against 20 the flange 16 and at its upper end against the bridge. In assembling the parts, the reinforcing ring is placed in the neck from the inner side thereof, and also the attaching ring 15, and the bridge is then placed in position with the shoulders 17 in the notches of the lugs 19, and the bridge secured in position by the rivets 4.

This construction of electrical fixtures is particularly advantageous in that it consists 30 of but a few simple parts which are readily assembled and when assembled the attaching ring is held from movement, without attaching to the base itself. It is further advantageous in that it can be readily attached 35 to a support by an interlocking movement.

What I claim is:

1. An electrical fixture comprising a canopy formed with a neck, a bridge extending diametrically across the neck at the inner end 40 thereof and secured at its ends to the canopy, the bridge having means for securement to a support upon partial rotary movement of the canopy and the neck also having means for securing the casing of a lamp socket there- 45 to, the last mentioned means comprising a ring and located in the neck, in the inner end thereof adjacent the bridge, the bridge and the ring having interlocking parts.

2. An electrical fixture, comprising a base 50 formed with a neck having an internal annular flange at its outer end, an annular attaching member for an electrical appliance located in the neck and thrusting against said flange, a bridge located in the base and ex- 55 tending across the passage of the neck, the bridge being formed with shoulders extending toward said member, and said member being formed with arms terminating in laterally turned lugs interlocking with said 60 shoulders.

3. An electrical fixture, comprising a base formed with a tubular neck having an internal annular flange at its outer end, a reinforcing ring located within the neck and 65 abutting against the flange, an attaching ring

for an electrical appliance located within the neck and the former ring, and abutting against said flange and a part located in the base and secured thereto at the inner end of the passage of the neck, said part engaging the inner edge of the reinforcing ring, the attaching ring and said part being formed with interlocking means to hold the attaching ring from turning.

In testimony whereof, I have hereunto signed my name, at Syracuse, in the county of Onondaga, and State of New York, this 24 day of May, 1924.

HARRY J. MOREY.
